COACH LOCK

Andrew Christian Andersen, Detroit, Mich., assignor to Ternstedt Manufacturing Company, Detroit, Mich., a corporation of Michigan

Application July 28, 1938, Serial No. 221,699

7 Claims. (Cl. 292—164)

This invention relates to an automobile door lock. The object is to provide a lock in which the outside handle can be used to retract the bolt by less effort than is required with the inside handle or is required to retract the bolt as it climbs the striker.

This arrangement is worked out on the principle of breaking a toggle, which is not broadly new, for this principle has been used in connection with cabinet or refrigerator latches and which have only one handle on the outside. But, so far as I know, the principle has never been applied to a coach lock nor worked out with a lock that has an outside handle and an inside handle.

In the drawings:

Figs. 1, 2, 3 and 4 are elevations of a lock with the cover plate removed and with the operating parts in different positions.

Referring to Fig. 1: 1 is the sliding bolt and 2 the inside retracting link. 3 is the outside rollback which bears on the abutment 4 on lever 5 to which is pivoted the bar 6 that has lug 7 slidable in slot 8 in the lever 9. This lever may be depressed, as shown in Fig. 4, either by the use of a key or by operating the push link 10. When depressed, it carries down the push bar 6 so that the outside handle is disconnected from the latch bolt as shown in Fig. 4. This much of the construction is old and is shown and claimed in the Andersen and Bowlus Patent 2,039,873. However, in the Andersen and Bowlus patent, the push bar operates directly on a lug which is part of the sliding bolt. Here, the push bar 6 operates on a lug 11 on toggle arm 12 which is connected with toggle arm 13. When the push bar 6 is pushed backwardly by the operation of the outside rollback, as shown in Fig. 2, it breaks the toggle downwardly to the position shown in Fig. 2. Torsion springs 14 and 15, which can be comparatively light springs, resist the breaking of the toggle and the movement of the outside rollback. But, when the striker or the inside handle through link 2 causes the retraction of the bolt, these before-mentioned springs have nothing to do with resisting the retraction but the heavy safety pin type of spring 16 has its arms pressed together, as shown in Fig. 3. In Fig. 3, the bolt has been retracted by the inside handle (not shown) operating on draft link 2. Toggle arm 12 swings on pivot 17 which is fastened to the lug portion 18 of the latch casing. Latch bolt 1 has a slot 19 which permits the bolt to slide past the fixed pivot 17. Link 2 has a slot 20 which permits the outside

handle or the striker to retract the bolt without operating on the link and inside handle.

The purpose of the spring 14 operating on lever 5 is to return the outside handle to its customary position. The spring 15 returns the toggle arms to the near straight line position shown in Figs. 1 and 4 as soon as the retractor 3 ceases to press on the push bar 6. The spring 14 returns the lever arm 5 and the push bar 6 to its initial position. Stop 25 engages with the toggle arm 12 to hold the arms in their near straight line position. The sum of the effort of springs 14 and 15 is less than the effort of the safety pin type of spring 16. When the bolt is retracted either directly by the inside handle draft link 2 or by means of riding over the striker, the two toggle arms lap each other, as shown in Fig. 3, by reason of the pin and slot connection 21 and 22. Toggle arm 13 is pivoted directly to the bolt by pivot 24. The arms of spring 16 are hooked over the two pivots 21 and 24 and, consequently, when the toggle shortens by overlapping, these two arms are drawn together, as shown in Fig. 3, against their natural bent. When the retracting effort is withdrawn, the arms expand out again, as shown in Figs. 1 and 4, and shoot the bolt outwardly.

I claim:

1. In a coach lock, a casing, a latch bolt slideable in the casing, an inside handle having an operating connection with said bolt, a pair of toggle arms having a pin and slot connection at the knee of the toggle, one arm fixedly pivoted to the latch casing, the other pivoted to the latch bolt, a spring tending to resist the toggle arms sliding into overlapped relation by direct retraction of the latch bolt, a second spring and stop tending to keep the toggle arms in a straight line position but slightly over center and an outside handle and operating connections arranged to break the toggle and thereby shorten it and retract the bolt.

2. In a coach lock, a casing, a latch bolt slideable in the casing, an inside handle having an operating connection with said bolt, a pair of toggle arms having a pin and slot connection at the knee of the toggle, one arm fixedly pivoted to the latch casing, the other pivoted to the latch bolt, a spring tending to resist the toggle arms sliding into overlapped relation by direct retraction of the latch bolt, a second spring and stop tending to keep the toggle arms in a straight line position but slightly over center and an outside handle and operating connections arranged to break the toggle and thereby shorten it and

- retract the bolt, said second spring being weaker than the first mentioned spring.
3. In a coach lock, a casing, a latch bolt slideable in the casing, an inside handle having operating connections with said bolt, a pair of toggle arms having a pin and slot connection at the knee of the toggle, one arm fixedly pivoted to the latch casing, the other pivoted to the latch bolt, a spring tending to resist the toggle arms sliding 10 into overlapped relation by direct retraction of the latch bolt, a second spring and stop tending to keep the toggle arms in a straight line position but slightly over center and an outside handle and operating connections arranged to break the 15 toggle and thereby shorten it and retract the bolt, said second spring being somewhat weaker than the first mentioned spring, and a spring biased lever cooperating with the outside handle in this action.
4. In a coach lock, a casing, a latch bolt slideable in the casing, an inside handle having operating connections with said bolt, a pair of toggle arms having a pin and slot connection at the knee of the toggle, one arm fixedly pivoted to the latch 20 casing, the other pivoted to the latch bolt, a spring and stop tending to resist the toggle arms sliding into overlapped relation by direct retraction of the latch bolt, a second spring tending to keep the toggle arms in a straight line position 25 but slightly over center, an outside handle and operating connections arranged to break the toggle and thereby shorten it and retract the bolt, said second spring being somewhat weaker than than the first mentioned spring, and a spring biased lever cooperating with the outside handle in this 30 breaking action, the spring acting upon the toggle plus the spring acting on the said lever exerting an effort less than the spring resisting the toggle arms sliding into overlapped relation.
5. In a coach lock, a casing, a latch bolt slideable

in the casing, a pair of toggle arms for retracting the latch bolt when the toggle is broken, a spring resisting the breaking of the toggle, an inside handle draft link directly connected to the latch bolt and a spring resisting the retraction of the latch bolt by the inside handle draft link or by the bolt head climbing the striker, said spring exercising greater effort than the spring resisting the breaking of the toggle and an outside handle having connections for breaking the toggle against the resistance of such lighter spring.

6. In a coach lock, a casing, a latch bolt slideable in the casing, a pair of toggle arms, one pivoted to the latch bolt and one to the casing, which arms form a toggle that can be broken at the knee by swinging action and which can have at the knee a sliding overlapping action, means for retracting the bolt directly, the toggle arms overlapping, a safety pin type of spring resisting the arms sliding in overlapping position and means for retracting the bolt by breaking the toggle at the knee.

7. In a coach lock, a casing, a latch bolt slideable in the casing, a pair of toggle arms, one pivoted to the latch bolt and one to the casing, which arms form a toggle that can be broken at the knee by swinging action and which can have at the knee a sliding overlapping action, means for retracting the bolt directly, the toggle arms overlapping, means for retracting the bolt by breaking the toggle at the knee, a relatively heavy spring tending to resist the overlapping of the toggle arms and thereby project the bolt and a lighter spring resisting the breaking of the toggle whereby less effort is required to retract the bolt by breaking the toggle than by retracting the bolt by an effort on the bolt, which is resisted by said relatively heavy spring.

ANDREW CHRISTIAN ANDERSEN.
